UNITED STATES PATENT OFFICE.

HENRY A. MARKS, OF WINTERHAVEN, FLORIDA.

OIL-BURNER.

1,110,329.

Specification of Letters Patent. Patented Sept. 15, 1914.

Application filed August 7, 1913. Serial No. 783,584.

To all whom it may concern:

Be it known that I, HENRY A. MARKS, citizen of the United States, residing at Winterhaven, in the county of Polk and State of Florida, have invented certain new and useful Improvements in Oil-Burners, of which the following is a specification.

My present invention relates to new and useful improvements in crude oil burners, and more particularly to that type of burners especially designed for use in orchards for dissipating frost and preventing injury to the fruit in case of a sudden fall in the temperature and known as orchard heaters, this invention being an improvement over the form of orchard heater disclosed in a patent granted to me March 19, 1912, and bearing Patent No. 1,020,616.

Heretofore orchard heaters have been constructed to create as heavy a smudge as possible irrespective of the heat given out, the idea being to protect the vegetation by the smudge rather than by the heat generated from the burning of the crude oil. At the present time, it is impossible to use smudge producing orchard heaters in many localities because of legislation against them as smoke nuisances, and for this reason I have constructed an orchard heater which will produce an intense heat with practically no smudge. In doing this, a further object which I have had in view is to so construct the heater that by a slight change in the position of the parts the heater may be employed as a smudge producer and, therefore, used as such in localities where heaters of that type are permitted.

A further object of my invention is to provide an orchard heater having a container and a burner, the burner and container being so arranged relatively and the container so shaped that every bit of crude oil in the container is ultimately consumed, no residue save a dry uncaked ash being left.

A still further object of my invention is to provide an orchard heater in which the combustion of the crude oil takes place under a direct draft and to provide means for regulating this draft. In this connection, I so arrange the draft openings of the burner proper that as the level of the oil is lowered in the container the proportion of air admitted to the burner is increased to insure combustion of the fuel

at the upper end of the burner under all circumstances.

A further object of my invention is to construct an orchard heater having a burner so arranged that the major portion of the crude oil is burned as a gas, the gas being generated by a relatively slow combustion at the surface of the crude oil in the container exterior of the burner. In this connection, I provide the orchard heater with a tubular member surrounding the burner in spaced relation thereto to form between it and the burner a circumferential draft chamber and between it and the wall of the container a preheating chamber for a portion of the crude oil fuel employed.

The burner construction includes a flue and the parts are so arranged that the gases generated in the heater are burnt in the flue. In order to provide means for varying the intensity of the heat generated by use of the heater, I have constructed this flue in such a manner as to render the same reversible, by which means the combustion may be made to take place in either a relatively large space or in a restricted space, as preferred, the former arrangement decreasing the intensity of the heat and creating a smudge.

A further object of my invention is to provide still another adjustment of the flue which will further increase the intensity of the heat and decrease the smudge, this object being accomplished by still a third positioning of the flue in inverted position and slightly at one side of the burner, the top of the heater being arranged to support and hold the flue in such position.

With these and other objects in view, my invention will be more fully described, illustrated in the accompanying drawings, and then specifically pointed out in the claims which are attached to and form a part of this application.

In the drawings: Figure 1 is a central vertical sectional view of my improved form of orchard heater; Fig. 2 is an inverted perspective view of a portion of the burner removed from the fuel container; Fig. 3 is a perspective view of the orchard heater complete; Fig. 4 is a fragmentary elevational view showing the flue in inverted position and supported slightly out of alignment with the rest of the burner, a portion of the top of the heater being broken away.

to more clearly disclose the positioning of the flue.

Corresponding and like parts are referred to in the following description and indicated in all the views of the accompanying drawings by the same reference characters.

The improved orchard heater forming the subject-matter of my present invention includes a burner, indicated as a whole by 10 the numeral 10, a container 11 for the crude oil, and an intermediate tubular member 12 positioned about the burner and in spaced relation between it and the walls of the container to provide a circumferential draft 15 chamber and a preheating chamber for the crude oil. The burner may be employed with practically any form of container, its use being in no way limited to the specific form shown in the drawings, but, in any 20 case, the tubular member 12 should be employed with the burner and for this reason should best be considered as part of the burner.

The container 11 is formed of sheet metal, 25 preferably steel, being substantially cylindrical in shape, open at its upper end and closed at its lower end. The closed lower end 13 of the container is preferably flatly formed centrally, but has its marginal edge 30 inclined upwardly, as at 14, to merge with the vertical wall of the container for a reason which will be hereinafter explained. The tubular member 12 tapers slightly from its upper to its lower end, being open at both 35 ends, and is provided at its upper end with an outwardly and downwardly extending supporting rim 15, this rim being permanently secured to the upper end of the tubular member 12 by an interlocking bead 16. 40 This rim is proportioned to fit snugly about the upper end of the container 11 to form, in effect, an air-tight closure between the container and the tubular member 12. The tapering of the tubular member is such 45 that the lower end of said member, which end is supported slightly above the bottom of the container, is in vertical alinement with the juncture of the flatly formed portion of the bottom with the upwardly inclined portion thereof.

The burner proper 10 includes a tubular member 17 and a flue 18. The tubular member 17, which may be called the inner tubular member to distinguish it from the outer tubular member 12, tapers from its upper to its lower end and is provided at its upper end with an outwardly and downwardly depending supporting rim 19, the lower edge of which seats in a circumferentially instruck depression 20 of the supporting rim 15 when the burner is in place. This supporting rim 19 forms the top or closure of the orchard heater, and it will be apparent that all air entering the heater must enter the same through openings provided in

this closure. The supporting rim 19 is secured to the tubular member 17 in the same manner that the supporting rim 15 is secured to the tubular member 12. The inner tubular member 17 is open at both ends and 70 is entirely disconnected from and free of the outer tubular member, its lower end extending slightly below the lower end of the outer tubular member. A plurality of draft openings 21 are formed in the inner tubular member in vertically spaced apart series, 75 each draft opening being diametrically spaced with respect to another draft opening of the same series. These draft openings are in the shape of isosceles triangles 80 and are formed in upright position with the vertices of one series extending slightly above the bases of the next series above. Furthermore, the draft openings of one series are formed in staggered relation to 85 the draft openings of adjacent series, as clearly shown in Figs. 1 and 2 of the drawings. The upper ends of the draft openings of the upper series terminate substantially at the level of the upper end of the outer 90 tubular member 12, while the upper end of the inner tubular member 17 extends considerably above said level.

The supporting rim 19 of the inner tubular member 17 includes a vertically disposed wall 22 and this wall at one side is provided with a series of elongated draft openings 23. A sliding plate 24 mounted for movement between guides 25 secured to the inner face of this wall provides means for regulating the admission of air through these draft openings, the plate being formed with openings 26 which in one position register with the openings 23. The adjustment of this plate is accomplished by means of an 105 outstruck ear 27 movable in a slot 28 formed in the wall 22. The wall 22 at a point opposite the draft openings 23 is provided with one or more openings 29 which, under some circumstances, act as auxiliary draft openings, and, under other circumstances, as 110 safety vents to permit escape of any surplus gas generated within the heater.

The flue 18, previously referred to, is open at both ends and tapered from one end to the other, its smaller end being proportioned to extend somewhat within the upper end of the inner tubular member 17 in the manner clearly shown in Fig. 1 of the drawings. The taper of this flue is such that when removed from the upper end of the tubular member 17 and inverted its larger end will seat upon the supporting rim 19 about the upper end of the tubular member 17. As will be later explained, the combustion of 125 the generated gas takes place in this flue and will be more or less perfect and rapid as the flue is inverted or upright position.

In addition to the above-mentioned ways of mounting the flue upon the heater, I pro- 130

vide still a third way, namely that illustrated in Fig. 4 of the drawings, in which the flue is inverted and seated upon the supporting rim or cover 19 slightly out of alignment with the inner tubular member or burner 17. In order to provide means for holding the flue in this position and prevent its displacement from the rim, I provide the supporting rim 19 with a pair of spaced 10 apart, upwardly extending studs 30 each provided with an arcuate slot 31, the curvature of which is the same as the curvature of the larger end of the flue. The flue when positioned as shown in Fig. 4 has its edge 15 portion seated in these slots and all movement of the flue is, therefore, prevented.

Having thus described the construction of my improved orchard heater, I will now explain the manner in which it is employed, 20 which is comparatively simple, although the principle upon which it operates is quite complicated.

In employing the orchard heater the container is nearly filled with the crude oil, 25 the outer tubular member 12 is positioned in the container and the inner tubular member with its cover 19 applied. A small amount of gasolene is then poured upon the surface of the crude oil in the inner tubular 30 member and ignited when the flue 18 is put in place. The gasolene passes through the draft openings 21 in the inner tubular member and therefore spreads over the surface of the crude oil, both within the inner tubular 35 member and in the space between the inner and outer tubular members. For this reason the entire surface of the crude oil, save for that between the outer tubular member and the container, is ignited, the 40 smoke and other products of combustion from the inner tubular member passing out through the flue 18 and creating a draft through the draft openings 23 causing the smoke and other products of combustion 45 from the burning crude oil outside of the inner tubular member to pass inwardly through the draft openings 21 and out through the flue. The heat generated by the burning of this gasolene and the subsequent 50 burning of the crude oil raises the temperature of the inner tubular member and the oil contained therein to such an extent that within a few minutes of the time the fuel is first ignited sufficient heat has 55 been generated to act in connection with the forced draft provided to generate large quantities of gas in the inner tubular member. As the quantity of gas so generated increases, the point at which it ignites gradually rises until when the heater is in full 60 operation the gas is burning in the upper part of the flue 18. Under these circumstances, there is absolutely no combustion at the surface of the fuel within the inner tubular member, although the fuel con-

tained between the inner and outer tubular members continues to burn. This continued burning of the fuel between the tubular members 12 and 17 preheats the fuel between the walls of the outer tubular member and the container and also highly heats the fuel contained within the inner tubular member to maintain a constant supply of gas. Gas is also generated, to a certain extent, between the inner and outer tubular members, but this gas, because of the rapidity of the draft, passes in a partially burnt condition into the inner tubular member and burns with the gas generated therein in the upper end of the flue. It will, therefore, 70 be seen that the space between the surface of the fuel, the tubular members 12 and 17 and the cover-forming rim 19 forms a combined hot draft or mixing and heating chamber, that the space within the upper 75 portion of the inner tubular member 17 above the fuel forms a gas generating chamber, and that the flue itself forms the combustion chamber of the heater. The amount of crude oil, burned as such in the 80 heating chamber, is comparatively slight in proportion to the amount of crude oil gasified and burned as gas in the flue, and it will, therefore, be clear that, although the heater utilizes crude oil as fuel, it is really 85 in effect a gas heater. For this reason, a much more intense heat may be obtained in proportion to the fuel consumed than is possible with crude oil heaters of the usual type. 90

It will, of course, be clear that the degree of heat may be regulated by adjustment of the sliding plate or damper 24 controlling the supply of air to the heater, as any decrease in the air supply will cause a more 105 moderate combustion of fuel in the heating chamber and, consequently, diminish the quantity of gas generated. With the draft openings fully exposed, a flame extending from three to four feet above the top of the 110 flue may be obtained.

The fuel level will, of course, be substantially the same in the preheating chamber, heating chamber and gas generating chamber, all of said chambers being in direct 115 communication with each other at their lower ends. By inclining the peripheral edge portion of the bottom of the fuel container, as shown at 14, all the fuel contained therein may be burned as the fuel is directed 120 inwardly toward the center of the container and is not in any way protected from the draft through the heating and draft chamber by the lower end of the outer tubular member 12, as would be the case if the bottom of the container were level throughout its entire extent.

The inner tubular member should be extended as close to the bottom of the container as possible and at a level below that 130

of the outer tubular member in order that the generation of gas may be maintained as long as possible, as it will be apparent that as soon as the fuel level in the container falls below the lower end of the inner tubular member 17, combustion at the surface of the fuel will take place throughout the entire area of the fuel and practically no gas will then be generated. If the flue 18 is inverted and placed directly in alignment with the inner tubular member 17, the draft therethrough will be increased and the combustion of the gas more rapid and complete, the result being an increase in heat and a decrease in smudge. If the flue, when inverted, is positioned as shown in Fig. 4, this effect will be still more pronounced, due to the excess of air to the flue 18 from above the heater, practically no smudge being produced when the flue is so arranged. Because of this arrangement, the orchard heater may be employed to protect vegetation by the generation of intense heat without an accompanying smudge when desired, or employed as a smudge producer, as preferred.

The specific shaping of the draft openings 21 and arrangement thereof is of great importance, particularly the arrangement of one series in such a manner that their upper ends extend slightly above the lower ends of the next series above. The triangular formation of the draft openings, together with their overlapping arrangement, not only insures an increasing draft as the fuel level in the heater is lowered by consumption of the fuel, but furnishes a draft which increases in proportion more rapidly than the decrease of fuel by consumption. This is important as the less fuel there is in the container the greater the draft necessary to insure proper gasification of the fuel. Moreover, the lighter oils in the crude oil will gasify more readily than the heavier oils and during the latter part of the operation it will be apparent that nothing but the heavier oils will remain and more air is, therefore, necessary for their proper and perfect combustion. It should be noted at this point that the sizes of the draft openings 21 vary, the openings in each series being somewhat larger than those in the series immediately above. This still further increases the proportion of air supplied to the burner as the fuel is consumed.

It will be understood that I do not wish to be limited to the specific construction shown, for which reason, I reserve the right to make any minor changes in construction, within the scope of the appended claims, without in the slightest degree departing from the spirit of my invention.

What I claim is:—

1. The combination with an oil container, 65 of a burner suspended within the container

and including an outer member, an inner member spaced from the outer member to form an intermediate air passage, the inner member having its side walls provided with apertures from its lower end to substantially 70 a level with the upper end of the outer member and both the members having their lower ends open.

2. An oil burner including an outer tubular member adapted to be suspended within 75 an oil container, an inner perforated tubular member spaced from the outer member to form an intermediate draft passage, the members being unconnected and open at their lower ends, and a flue forming an upper continuation of the inner tubular member. 80

3. The combination with an oil container, of a cover therefor, and a tubular member 85 opening at its upper end through said cover, said cover and tubular member having draft openings, the draft openings of the tubular member being triangular in shape and each with one angle uppermost.

4. The combination with an oil container, 90 of a cover therefor, and a tubular member opening at its upper end through said cover, said cover and tubular member having draft openings, the draft openings of the tubular member being triangular in shape, arranged 95 in staggered vertically spaced apart series with the upper ends of one series extending above the lower ends of the next higher series.

5. In an orchard heater, a container having a substantially vertical side wall and a bottom the marginal edge of which is inclined upwardly to merge with the side wall at an angle thereto, and a burner suspended 100 within the container and closing the top 105 thereof.

6. In an orchard heater, a container having a bottom the marginal edge of which is inclined upwardly, and a burner suspended 110 within the container and closing the top thereof, said burner including an outer tubular member having a depending supporting rim engaging over the upper edge of the container, an inner tubular member having draft openings, and a downwardly depending supporting rim engaging over the rim of the first mentioned tubular member, the lower edge of the outer tubular member being in vertical alignment with the inner portion of the inclined marginal part of the 115 bottom, and a flue engaging in the upper end of the inner tubular member and forming a continuation thereof. 120

7. The combination with an oil container, 125 of an outer tubular member having an outwardly and downwardly depending supporting flange engaging the container to suspend the member therein, and an inner tubular member provided with draft openings and having an outwardly and downwardly 130

depending supporting rim removably seating on said flange to suspend the inner tubular member within the outer tubular member, the said rim being provided with draft openings.

8. An orchard heater including an oil container, spaced inner and outer tubular members open at their ends suspended within the container, a rim carried by the upper end of the outer tubular member and engaging the upper end of the container to provide therewith and with the outer tubular member a circumferential preheating chamber, a rim carried by the upper end of the inner tubular member and removably seating on the rim of the outer tubular member to form with said members a circumferential air passage and heating chamber, the inner tubular member being provided with draft openings and the rim thereof also being provided with draft openings, and a flue seating in and forming a continuation of the inner tubular member, the upper portion of said inner member providing a gas generating chamber and the flue a combustion chamber.

9. An oil burner including an outer tubular member, means for supporting the outer tubular member in an oil container, an inner tubular member provided with draft openings, an outwardly and downwardly depending supporting rim carried by the inner tubular member adapted for engagement with the supporting means of the outer tubular member and to form a cover for the container, said rim being provided at one side with spaced studs having arcuate slots, and a tapered flue proportioned to seat with its smaller end in the upper end of the inner tubular member or with the edge of its larger end in the slots of the studs.

10. The combination with an oil container, of a cover therefor, and a tubular member opening at its upper end through said cover, said cover having draft openings and said tubular member having draft openings wider at their lower than at their upper ends.

11. The combination with an oil container, of a cover therefor, and a tubular member opening at its upper end through said cover, said cover and tubular member having draft openings, the draft openings of the tubular member being arranged in se-

ries, the openings of each series being larger than the openings of the series immediately thereabove.

12. In an orchard heater, a container having a bottom, the marginal edge of which is inclined upwardly, and a burner suspended within the container and including inner and outer tubular members, the lower edge of the outer tubular member being substantially in vertical alinement with the inner portion of the inclined marginal part of the bottom of the container.

13. The combination with an oil container, of a cover therefor, means for supplying air to the container, and a tubular member opening through the cover and extending within the container, said tubular member within the container being provided with draft openings tapering from their lower to their upper ends.

14. An oil burner including a tubular member provided with spaced apart series of draft openings, the draft openings being wider at one end than at the other, said burner being adapted for normal suspension within an oil container with the wider ends of the openings lowermost.

15. An oil burner including a tubular member adapted to be suspended within an oil container and provided with series of draft openings, the openings of each series being larger than those of the series immediately above.

16. An oil burner including a tubular member adapted to be suspended within an oil container and provided with series of draft openings, each wider at its lower than at its upper end, the upper ends of the openings of one series extending above the lower ends of the next higher series.

17. In an orchard heater, an oil container, a cover having an opening and spaced slotted studs, and a tapered flue proportioned to seat with its smaller end in the opening of the cover or with the edge of its larger end in the slots of the studs to project partially over the opening of the cover.

In testimony whereof I affix my signature in presence of two witnesses.
